UNITED STATES PATENT OFFICE.

JESSE H. GLEASON, OF ATLANTA, GEORGIA.

CASKET.

1,387,974.

Specification of Letters Patent. Patented Aug. 16, 1921.

Application filed September 19, 1918. Serial No. 254,826.

To all whom it may concern:

Be it known that I, JESSE H. GLEASON, a citizen of the United States, residing at Atlanta, in the county of Fulton and State of 5 Georgia, have invented new and useful Improvements in Caskets, of which the following is a specification.

This invention has reference generally to improvements in that class of inventions 10 known as undertaking and more particularly relates to a casket.

It is the principal aim and object of the present invention to provide a device of the above mentioned character designed so that 15 when closed a seal will be effected between the top and the body to render the casket air tight and water proof.

It is an equally important object of the present invention to provide a device of the 20 above mentioned character wherein the metallic sides, bottom and top are reinforced in such a manner that when the molding and trimming are applied to the outer surfaces of the said parts, the latter will not be punctured by the fastening means for the molding, etc., thus preventing the access of air 25 and water into the metallic body of the casket.

More particularly this invention consists 30 in the provision of a device of the above mentioned character wherein coöperative sealing members are connected to the adjacent edges of the top and body to provide for an effective seal therebetween at the time 35 the top is closed.

It is a more specific object of this invention to provide a device of the above mentioned character wherein improved coöperative bracing and fastening means are employed 40 between the body of the casket and the top.

It is an additional object of this invention to provide a device of the above mentioned character which is simple in construction, 45 thoroughly reliable and efficient in its purpose and inexpensive in manufacture.

Other objects will be in part obvious and in part hereinafter set forth.

The invention accordingly consists in the 50 features of construction, the combination of elements and the arrangement of parts which will be exemplified in the construction hereinafter described and the scope of the application of which will be indicated in the appended claims.

The invention is clearly illustrated in the accompanying drawings, in which:

Figure 1 is a side elevation of the improved casket.

Fig. 2 is a vertical transverse sectional view taken on line 2—2 of Fig. 1.

Fig. 3 is a longitudinal central sectional view of the invention.

Fig. 4 is a horizontal sectional detail taken on line 4—4 of Fig. 2.

Fig. 5 is a horizontal sectional detail taken on line 5—5 of Fig. 2, and

Fig. 6 is a fragmentary perspective detail of the device.

Similar characters of reference are employed in all of the above described views, to indicate corresponding parts.

Referring now, more particularly, to the accompanying drawings there is provided a casket which consists of a wooden base 1 on the upper surface of which is supported a sheet metal base lining 2 provided with upright side and end flanges 3 which are soldered respectively to the sides 4 and end pieces 5, both of sheet metal, and these metal sides and end pieces are in turn anchored by suitable fasteners 6 to the adjacent edges of the base 1. The parts enumerated form the body of the casket. Wooden reinforcing strips are disposed longitudinally and against the inner surfaces of the sides 4 and are held in position by metallic supports 8 which fit snugly about the strips and are formed with attaching flanges 9 in turn soldered to the inner faces of the sides 4. Handles 10 are employed and are connected by suitable fasteners 11 to the sides, said fasteners passing through the sides and being anchored in the wooden reinforcing blocks.

It is to be observed that the fasteners 10 penetrate the sides 4 and enter the wooden reinforcing strips but do not reach the metallic supports 8. Means are thus provided for attaching the handles to the casket without the attaching means entering the interior of the casket. The reinforcing blocks serve as a strengthening means to prevent the distortion of the casket when it is made of this gage metal and the metallic supports, aside from holding the reinforcing blocks in place serve to prevent the entrance of moisture into the casket at points where the fasteners secure the handles to the casket. Metal angle strips 12 and 13 are soldered to the inner and outer faces of the 110

sides and ends 4 and 5 near the upper edges thereof, the horizontal portions 14 of said angle strips lying flush with the upper edges of the sides and ends as indicated. Upper 5 molding strips 15 are anchored to the horizontal portions 14 of the angle strips 12 by suitable fasteners 16 while lower molding strips 17 are anchored by suitable fasteners 18 against the outer surfaces of the sides and 10 ends and to the base 1. A sealing member 19 is employed and is desirably of an inverted V-shaped configuration in cross section being formed with attaching flanges 20 which are soldered to the upper faces of the 15 horizontal portions 14 of the angle strips 12 and 13 for a purpose that will hereinafter be apparent.

A top generally designated by the numeral 21 is employed and consists of a metallic frame 22 of a rectangular configuration. This frame is constructed desirably from sheet metal having the main portion inclined as at 23 and formed at its upper and lower or marginal edges with horizontally extending 20 flange portions 24 and 25. A metal angle strip 26 is soldered to the under surface of the inclined body portion 23 of the frame and extends throughout the length thereof co-operating with the adjacent lower portion 25 of the frame to provide a sealing member which in turn co-operates with the sealing member 19 in a manner that will hereinafter 30 become apparent. A lower or main molding strip 27 is anchored by suitable fasteners 28 to the lower flange 25 and has secured near the upper surface thereof an upper or supplemental molding strip 29 by means of suitable fasteners 30. The molding strips 27 and 29, of course, extend entirely around the top.

In swingably connecting the top to the body hinges 31 are employed the leaves of which are respectively anchored in recesses 32 in the molding strip 15 and in recesses in 45 the molding strip 27, said hinges being positioned, of course, at one side edge of the body and the top. A covering 33 of a suitable type is arranged about the top and the body while a cover or closure plate of a conventional construction is fitted within the 50 top.

With a view toward bracing the top with respect to the body upright posts 34 are anchored in metal sockets 35 in turn soldered 55 at suitable spaced intervals to the base lining 2 and reinforced with respect to the sides by means of braces 36. Co-operating with the upper ends of the posts are lugs 37 which depend from the frame 22 and abut the posts at the time the top is completely

closed so as to be supported by the posts. The preferred means for connecting the lugs to the frame consists in metal bracket arms 38 which are formed with attaching flanges 39 designed to be soldered to the frame 22. 65 Connecting strips 40 are also employed and have their respective ends secured by fasteners 41 to the upper molding strips 29 and to the lugs 37 as indicated. Hook and eye connections 42 are carried by the posts and 70 the lugs respectively and engage with each other subsequent to the closing of the top and preparatory to the insertion of the cover or closing plate. Suitable upholstering is carried within the body of the casket and 75 disposed as shown.

In closing the casket it is desired that a suitable sealing mixture be first applied to the sealing member 19. Subsequently, of course, the top may be swung so that the 80 sealing member provided by the lower portion of the body 23 of the frame, the flange 25 and the angle strip 26, may seat on and seal against the sealing member 19 providing an air tight and water proof seal between the top and the body as is apparent.

It is believed in view of the foregoing description that a further detailed description of the operation of the invention is entirely unnecessary. Likewise it is believed that 90 the advantages of the invention will be readily apparent.

What is claimed is:

1. A casket including a body composed of a base, a base lining disposed thereabove and formed of metal, metallic sides and ends secured to the base lining and anchored to the base, angle strips secured to the upper edges of the sides and ends, and a sealing member of an inverted V-shaped configuration soldered to the angle strips, a top swingably connected to the body and including a metallic frame, and angle strips secured to the inner surface of the frame and co-operating therewith to provide a sealing member which in turn co-operates with the sealing member of the body upon the closing of the top.

2. A casket embodying a base, side and end walls upstanding from the base, posts disposed within the casket and in spaced relation to each other and in spaced relation to the side walls, a hinged top frame swing- 110 ing down into abutting position with said posts, and upholstery disposed within the 115 casket and in the plane of the inner faces of said posts, as herein shown and specified.

In testimony whereof I affix my signature.

JESSE H. GLEASON.
